CLOTHESPIN

Ralph J. Wilson, Cleveland, Ohio, assignor of
one-half to Virgil P. Cramer, East Cleveland,
Ohio

Application July 3, 1941, Serial No. 401,003

1 Claim. (Cl. 24—139)

This invention is for a wire clothes pin and is an improvement upon that shown in the U. S. Letters Patent No. 260,297 of June 27, 1882, to Johnston.

There have been numerous patents granted upon wire clothes pins, notably that to Johnston cited above, but none of them has appeared upon the market, so far as I am aware, and it is believed that none of the prior forms of such device has been sufficiently practical to satisfy the public.

It is therefore the object of the present invention to devise a wire clothes pin that possesses all of the desired practical advantages including that of a comparatively low purchase price so as to meet popular favor in every respect.

One particular object of the present invention is to devise a wire clothes pin of such form that a large number of them can be held at one time upon the finger or thumb of the hand of the user and can be readily transferred from the finger to the thumb of the same hand or vice versa, as may be desired, at the same time permitting the rest of the hand to be employed in the usual manner, while at the same time the pins are readily available for quick use.

Another object is to so devise such a clothes pin that there will be no danger of the clothes becoming caught in any part thereof while hanging upon the clothes line.

A further object is to devise such a clothes pin of practically flat form throughout its entire extent so that they can be readily packed for shipment and a number of them can be readily held upon the finger of the hand of the user in the manner above explained.

A still further object is to devise such a clothes pin that possesses most efficient resilience for the operation of the same in gripping and holding the clothes upon the clothes line.

Finally, it is the object of my invention to devise such an article that can be manufactured in a practical manner and sold at a popular price and that will last practically indefinitely.

Other objects will appear from the following description and claims when considered together with the accompanying drawing.

Fig. 1 is an elevation of my improved clothes pin;

Fig. 2 is an edge view thereof;

Fig. 3 is a view in vertical section therethrough;

and

Fig. 4 is a perspective view of the same.

It is to be understood that the present form of disclosure is merely for the purpose of illustra-

tion and that there may be devised various modifications thereof without departing from the spirit of my invention as herein set forth and claimed.

My present improved form of clothes pin is formed from a single piece of resilient, galvanized wire which is first curved at the top, as indicated at 1, from which point the two halves of the wire are extended downwardly so as to form the parallel sides 2 and 3 of the upper loop 4, thence inwardly in parallel relation past each other so as to form the bottom of the loop, these two parallel bottom portions 5 and 6 of the loop 4 being close to each other and located to the front and rear of each other in the same horizontal plane. 10 Thence the portions of the wire are bent downwardly from the lower outer corners of the loop 4 so as to form the outer sides 7 and 8 of the lobes which are indicated by reference numeral 9, these lobes being located immediately below the loop 4. The wire at the bottoms of the lobes are turned upwardly and inwardly, as indicated at 10 and 11, so as to form the mouth 12 to receive the clothes line between the lobes when the clothes pin is applied to the line. Thence the wire portions are extended upwardly in close 20 parallel relation so as to form the inner sides 13 and 14 of the lobes, thence outwardly at the upper ends thereof so as to terminate in the outwardly extending portions 15 and 16 which are parallel to and spaced from the bottom portions 5 and 6 of the loop 4, the portions 15 and 16 stopping short of the outer sides 7 and 8 of the lobes.

In placing this clothes pin upon the clothes line, it will occupy position at right angle to the length of the line and will maintain this same position at all times during use. The clothes and clothes line will be received in the mouth 12 and, upon forcing the pin onto the line, the resilience of the loop 4 will permit the lobes 9 to separate bodily sufficiently for the clothes and line to be received between the inner sides 13 and 14 of the lobes. Then as the pin is forced downwardly upon the line, it will be observed that the inner sides 13 and 14 of the lobes will be caused to move individually outwardly away from each other towards the outer sides of the lobes, whereupon the clothes and line enter the substantially triangular space 17 between the bottom of the loop 4 and the outwardly extending end portions 15 and 16, in which position the clothes and line are maintained with what might be regarded as a three-point engagement. It is to be understood that, as the pin assumes this final position, the inner sides 13 and 14 of the lobes move inwardly

towards their original position as far as possible, thereby assuming effective engagement of the clothes upon the line in the position just described.

Then, when it is desired to remove the clothes from the line, the pins are merely pulled upwardly and the reverse action takes place in the resilient portions thereof, as compared with the action above described. The removal of the pins may be expedited by passing the thumb of the hand through successive pins, that is through the loops 4, and thereby removing the same without any appreciable effort, while at the same time quite a number of them can be collected upon the one thumb before having to deposit the same preparatory to repeating the same operation. In this way there is saved considerable time and there is realized quite a convenience.

This particular form of clothes pin possesses several important practical advantages, as compared with any and all other wire clothes pins that are known to me. The loop at the top is of such size and form that a large number of these pins can be readily placed upon the one finger of the hand of the user and readily transferred one at a time from the outside to the inside of the same hand when it is desired to use the same. Also, when it is desired to remove the clothes pins from the clothes line, they can be gathered upon the thumb of the user's hand, as above explained. This improvement is made possible by several contributing factors.

First, the loop 4 is of substantially the same width as the combined width of two lobes together; which means that the clothes pin is of substantially the same width throughout its entire extent, this shape greatly facilitating the turning of the pins about the finger or thumb of the hand so as to bring them from the storage position at the back of the hand to the inside thereof for application to the clothes line. That is, only the one pin that is being used at any given moment will occupy position within the hand, the other pins extending outwardly from the back of the hand, while the finger extends freely through the loops 4.

Second, the entire pin occupies substantially the same flat plane throughout, which makes possible the storing of a large number of these pins upon the same finger of the user's hand in the manner explained.

Third, the curved form of the loop 4 at its top part greatly facilitates the handling of these pins in the manner above described, especially the turning of the pins about the finger as they are brought from the back of the hand to the inside thereof for use, as explained.

Not only does the enlarged loop 4 contribute to the feature just mentioned, but this particular form of loop with its curved top adds also to the degree of resilience, which is very essential in the spreading action of the lobes 9 in the manner explained above.

Furthermore, the relative size and shape of

the loop 4, with respect to that of the lobes 9, provides what might be regarded as a "stream-lined" form of pin along the two sides throughout the entire length thereof, with the result that there are no recesses into which the clothes might accidentally become caught as they are whipped by the wind. As a result, my present form of pin is more apt to ensure fully free suspension of the clothes from the points of attachment to the line so as to have the most efficient exposure to the drying elements; and this same feature means also that there is less danger of the clothes becoming torn while upon the line.

The substantially flat form of my clothes pin also facilitates the packing of the same for transportation as they will occupy minimum space per unit and there will be a minimum loss of packing space within a container. This means, of course, a saving which may be reflected in the purchase price.

Another advantage consists in the fact that my clothes pins are not apt to become entangled with each other when thrown together in the same container, this by virtue of the practically flat and stream-lined form of my present clothes pin, as above described.

What I claim is:

A clothes pin comprising a single piece of resilient wire bent downwardly in the middle thereof so as to form a single upper resilient loop, the two halves of the wire extending thence inwardly in opposite directions past each other in close parallel arrangement to form the bottom of the loop, thence downwardly at the two sides as virtual continuations directly from the outer bottom corners of said loop so as to form the outer sides of duplicate resilient lobes immediately below said loop, thence inwardly and upwardly to form a mouth at the bottom of the clothes pin for receiving the clothes and the clothes line between said lobes, thence upwardly in close parallel relation to each other so as to form the inner sides of said lobes, thence outwardly from each other at the upper inner corners of said lobes in substantially parallel adjacent spaced relation to the bottom of said loop and terminating short of the outer sides of said lobes, thereby providing a space with three-point engagement for the clothes and clothes line between the upper inner corners of said lobes and the bottom of said loop, said lobes being resiliently movable bodily towards and from each other by virtue of the resilience of said loop, and the inner portions of said lobes being resiliently movable individually with respect to the outer sides of said lobes by virtue of the resilience of said individual lobes, said loop being of suitable dimensions to permit the same to be received freely upon the finger or thumb of the hand of the user, and said loop and lobes occupying substantially the same single plane throughout so as to give a substantially flat form to the entire clothes pin.

RALPH J. WILSON.
